UNITED STATES PATENT OFFICE.

HARRY A. LOOMIS, OF SAN JOSE, CALIFORNIA.

DESIGN FOR A BALLOON TOY.

60,553.

Specification for Design.

Patented Mar. 7, 1922.

Application filed February 23, 1921. Serial No. 447,321. Term of patent 3½ years.

To all whom it may concern:

Be it known that I, HARRY A. LOOMIS, a citizen of the United States, residing in San Jose, county of Santa Clara, and State of California, have invented a new, original, and ornamental Design for Balloon Toys, of which the following is a specification, reference being had to the accompanying drawing, forming part thereof.

The figure shows a front elevation of a balloon toy showing my new design.

I claim:

The ornamental design for a balloon toy, as shown.

HARRY A. LOOMIS.
